(57) **CLAIM**

The ornamental design for a dock for electronic devices, as shown and described.

DESCRIPTION

FIG. 1 is a top, front, right side perspective view of a dock for electronic devices, showing our new design;

FIG. 2 is a left side elevation view thereof;

FIG. 3 is a right side elevation view thereof;

FIG. 4 is front elevation view thereof;

FIG. 5 is rear elevation view thereof;

FIG. 6 is a top plan view thereof; and,

FIG. 7 is a bottom plan view thereof.

The equal-length broken lines depict portions of the dock for electronic devices that forms no part of the claimed design. The dash-dot-dash lines represent a boundary and form no part of the claimed design.

1 Claim, 7 Drawing Sheets
